UNITED STATES PATENT OFFICE.

MILLARD H. TONCRAY, OF DETROIT, MICHIGAN, ASSIGNOR TO HUDSON MOTOR CAR COMPANY, OF DETROIT, MICHIGAN, A CORPORATION OF MICHIGAN.

DOOR ASSEMBLY.

Application filed April 10, 1926. Serial No. 101,079.

This invention relates to doors for closed automobile bodies and has among its general objects to provide a door of attractive appearance and having the requisite strength and 5 rigidity, which door, with the exception of the window glass, trim, and other accessory parts, is composed entirely of metal, which can be quickly and inexpensively constructed by the assembly of sheet metal 10 stampings themselves simple and inexpensive of production by standard methods, and which can be readily provided with a baked enamel or other finish.

Other and more particular objects of the 15 invention, together with means whereby the latter may be carried into effect, will best be understood from the following description of a preferred embodiment thereof illustrated in the accompanying drawings. It will be 20 understood, however, that the particular construction shown and described has been chosen for illustrative purposes merely, and that the invention, as defined by the claims 25 hereunto appended, may be otherwise embodied without departure from the spirit and scope thereof.

In said drawings:

Fig. 1 is a perspective view of the main door assembly in the condition in which it is 30 enameled or otherwise finished.

Figs. 2 and 3 are enlarged sections taken substantially on the lines 2—2 and 3—3 respectively, Fig. 1.

Fig. 4 is an enlarged fragmentary perspective view showing the construction at one of the upper corners of the door.

Fig. 5 is a further enlarged section taken substantially on the line 5—5, Fig. 1.

Fig. 6 is a perspective view, partly broken 40 away, of the substantially completed door.

Figs. 7, 8, 9 and 10 are enlarged sections taken substantially on the lines 7—7, 8—8, 9—9 and 10—10, respectively, Fig. 6.

Fig. 11 is a detail sectional view taken substantially on the line 11—11, Fig. 10.

Fig. 12 is a fragmentary perspective view illustrating the boxed construction at the bottom of the door.

Fig. 13 is a detail section on the line 13—13, 50 Fig. 7.

Referring to Figs. 1 to 5 and 12, the door assembly therein shown comprises two uprights 20 and 21 carrying window guides 22,

a header 23, a bottom reinforcing cross member 24, an outside panel 25, and a combined regulator board and inside panel 26. The upright 20 constitutes the door hinge pillar and carries one of the elements of a hinge by which the door is connected with the body hinge pillar, not shown. The hinge or hinges 55 may be of any type or construction, but as shown in Figs. 5 and 9 the door hinge pillar 20 has secured thereto, as by bolts 27, one section 28 of a hinge of the type more fully disclosed in a prior application filed November 30, 1925, Serial No. 72,219, together with a cover 29 for the hinge. The upright 21 constitutes the door latch pillar which is located at the free edge of the door. The pillars 20 and 21 comprise sheet metal stampings and 60 are preferably of the open cross-section shown, having web portions disposed transversely of the door and determining its thickness and inner and outer flanges disposed parallel with the inner and outer faces of 65 the door respectively, the outer flange 30 of the latch pillar 21 being turned outwardly or away from the body of the door to engage the outer face of the body latch pillar or door jamb (not shown). The lower portions of 70 the inner flanges of the pillars 20 and 21 are preferably formed with integral offset lips 31 (see particularly Fig. 10) for a purpose hereinafter explained. The header 23, which connects the pillars 20 and 21 at the top, also 75 preferably comprises a sheet metal stamping of channel cross-section disposed with the web vertical and the channel opening outwardly, the upper leg of the channel being 80 formed with an upstanding flange 32 designed to overlap the header of the door opening (not shown), and the ends of the web being formed with forwardly turned ears 33 85 which, in the assembled door, are spot-welded to the pillars 20 and 21, as most clearly shown in Fig. 4. The window guides 22 are also composed of sheet metal and comprise portions channel-shaped in cross section to receive the window runs, and flanges 34 secured, as by rivets 35, to the outwardly turned 90 edges 19 of the inner flanges of the pillars 20 and 21. The window guides 22 are preferably 95 spot-welded at their upper ends to the header 23, as indicated in Fig. 4, and may be further braced below their upper ends by 100 brackets 36 connecting them with the webs of 105

the pillars 20 and 21, as shown in Fig. 5. The inside bottom reinforcing member 24 (see particularly Figs. 2 and 12) comprises a sheet metal member of angular cross section 5 having a vertical leg and an upper horizontal leg, the vertical leg being preferably of considerably greater length than the horizontal leg. The horizontal leg of the cross member 24 is formed at its free edge with an upper standing flange 37 and at its ends with upper standing ears 38, while the vertical leg is formed at its ends with outwardly turned flanges 39. The outside panel 25, which connects the pillars 20 and 21 at the outer side 10 of the door, comprises a sheet metal stamping of the desired form and outline of the exterior of the door and is formed in its upper portion with a window opening 40, the edges of which are turned inwardly, as shown at 15 41. At its upper edge the outside panel 25 is crimped over the flange 32 of the header 23 as shown at 42 (see particularly Fig. 3). One of the vertical edges of the panel 25 is similarly crimped over the flange 30 of the door 20 latch pillar 21 as shown at 43 (see particularly Fig. 5), while the opposite vertical edge 25 44 is turned inwardly and riveted or spot-welded to the web of the door hinge pillar 20. The combined regulator board and inside 30 panel 26, which connects the pillars 20 and 21 at the inner side of the door below the window opening 40, is also composed of sheet metal and is formed with a substantially central opening 45 surrounded by an inturned stiffening flange 46 and at opposite sides of said 35 opening with surfaces 47 for the attachment of the window operating mechanism, said surfaces being symmetrically arranged so that the same panel can be used interchangeably for doors at either the right or the left side of the body. At its lower end the inside panel 26 is turned outwardly (or toward the outer side of the door) as shown at 48 (see particularly Figs. 2 and 12), thence downwardly as shown at 49, thence again outwardly as shown at 50, and finally again downwardly as shown at 51 to form a bottom flange 45 to overlap the threshold (not shown). The vertical edges of the inside panel 26 are secured by rivets 52 to the inner flanges of the door pillars 20 and 21, said panel and flanges being provided at the time of their formation with die-located holes to receive said rivets and thereby relatively position the parts. 50 The lower edge of the vertical leg of the member 24 is secured, as by rivets 53, to the downwardly turned portion 49 of the inside panel 26, while the flange 37 is likewise secured, as by rivets 54, to the outer face of said 55 panel at an elevation considerably above the outwardly turned portion 48 of the latter. The ears 38 and flanges 39 of the member 24 are secured, as by rivets 55 and 60 respectively, to the webs of the door pillars 20 and 21. The riveted joints between the member 24 on the one hand and the inside panel and door pillars on the other may, if desired, be reinforced by spot-welding. The lower edge of the outside panel 25 is crimped over the bottom flange 51 of the inside panel 26 as 70 shown at 61. Secured, as by rivets 62, to the top horizontal leg of the reinforcing cross member 24 is a holder 63 for a rubber or other window bumper 64 (Fig. 7) to engage the lower edge of the window glass, hereinafter 75 referred to, when the latter is lowered. The parts above referred to (with the exception of the window bumper 64) are assembled with one another in a suitable jig or otherwise and are secured together in the 80 manner described. By reason of the pre-located holes for the rivets 52, the parts can be relatively positioned with great accuracy and properly squared with one another whether a jig or form be employed or not. 85 The reinforcing cross member 24, in conjunction with the lower portion of the inside panel 26, the outwardly turned portion 48 of the latter, and the pillars 20 and 21, forms, at the bottom of the door, a transversely ex- 90 tending, completely boxed stiffening section or hollow box girder member which provides a rigid connection between the pillars independently of the outside panel. This feature of the construction is of great importance 95 and advantage since it gives to this portion of the door the rigidity required to stiffen the whole structure, permits the use of pillars of open cross section which can be readily produced by simple stamping operations, prevents warping and weaving of the door, and insures the retention by the latter of its pre-determined shape and its accurate fit in the 100 door opening. 105 The parts of the assembly thus produced are all of metal and may be enameled and baked or otherwise finished without danger of injury thereto. 110 Thereafter (see Figs. 6 to 12) the window glass, trim, and accessory parts are applied to the assembly above described. The window regulating mechanism, which may be of any approved type and which is generally indicated at 65 in Fig. 6, and the door latch or lock (hereinafter further referred to) are 115 secured to the appropriate end of the inside panel 26, the window bumper 64 is applied to its holder 63, and felt or rubber runs 66 are applied to the window guides 22. The window glass 67, with the usual channel 68 at its 120 lower edge, is then dropped into the window runs and guides from the top and its channel 68 engaged with the arm of the operating mechanism 65, this insertion of the glass from the top being permitted by the location of the header 23 outwardly of the plane of the guides, as shown most clearly in Fig. 4. A door trim panel 69, which may comprise a sheet of veneer or fibre board covered with 125 suitable fabric, is then applied to the inner 130

- face of the inside panel 26, the opposite vertical edges thereof being inserted under and held in place by the lips 31 on the inner flanges of the pillars 20 and 21. A belt trim molding 70 is then secured by screws 72 to the upper edge of the inside panel 26, said molding having an integral offset lip 71 overlapping the upper edge of the trim panel 69 and holding the latter in place at the top. 10 The screws 72, or certain of them, may also, if desired, be employed for the purpose of securing in place a pull-to handle 86. The belt trim molding 70 is preferably provided with a cushioning strip 73 engaging the inner face 15 of the window glass 67, while a similar outside cushioning strip 74 is preferably secured to a flange 75 at the lower side of the inturned rim 41 of the window opening 40 in the outside panel 25. The lower edge of 20 the trim panel 69 is held in place by a molding 76 secured by screws 77 to the inside panel 26 adjacent the outwardly turned portion 48 of the latter, said molding carrying a rubber seal 78 to engage the top of the threshold. 25 After the insertion of the window glass 67, the top of the door is closed and finished by a trim header 79 (see particularly Fig. 8) secured by screws 80 to the upper leg of the header channel 23. The trim header 79 is 30 preferably composed of sheet metal of the angular form shown and includes an upwardly turned bottom flange 81 to which is secured, as by screws 82, a holder 83 for a rubber window header 84 to engage the upper 35 edge of the glass 67. If desired, additional screws 80^a may be employed to secure the ends of the trim header 79 to ears formed at the upper ends of the inner flanges of the pillars 20 and 21. 40 The door latch may be of any approved type including a latch bolt 85 projecting through an opening in the web of the latch pillar 21 and operable from the outer and inner sides of the door respectively by suitable outside and inside handles (not shown) 45 through mechanism (not shown in detail) held by a casing 88 secured to the latch pillar 21 and inside panel 26 by screws 89 and 90 respectively, said casing carrying clinch nuts 50 87 for the attachment of the escutcheon plate for the inside handle. A key operated lock is preferably provided for locking the latch bolt from the outside, said lock comprising a barrel 91 held between the outside panel 25 55 and an inside plate 92 spot-welded thereto and carrying clinch nuts 93 for the attachment of the escutcheon plate for the outside handle. 60 The door is also preferably provided with bumpers 94 to engage the door jamb, which bumpers may be of the type disclosed and claimed in application Serial No. 100,586 filed April 8, 1926, and comprising rubber blocks adjustably secured within the latch pillar 21 and projecting through openings in

the latter at the junction of the web and inner flange thereof.

Having thus described my invention, I claim:

1. A sheet metal door for automobile bodies including a pair of upright pillars and a hollow sheet-metal box girder member forming a rigid connection between said pillars adjacent the bottom. 70
2. A sheet metal door for automobile bodies including a pair of upright pillars of open cross-section and a hollow sheet-metal box girder member forming a rigid connection between said pillars adjacent the bottom. 75
3. A sheet metal door for automobile bodies including a pair of upright pillars, a panel connecting said pillars, and a sheet metal member secured to said pillars and panel and forming therewith a boxed stiffening section adjacent the bottom of the door. 80
4. A sheet metal door for automobile bodies, including a pair of upright pillars, an outside panel connecting said pillars at the outer side of the door, an inside panel connecting said pillars at the inner side of the door, and a reinforcing member secured to said pillars and inside panel and forming therewith, and independently of said outside panel, a boxed stiffening section adjacent the bottom of the door. 85
5. A door for automobile bodies, including a pair of upright metal pillars, an outside panel connecting said pillars at the outer side of the door, a sheet metal inside panel connecting said pillars at the inner side of the door, and a sheet metal reinforcing member secured to said pillars and inside panel and forming therewith a boxed stiffening section adjacent the bottom of the door. 90
6. A door for automobile bodies, including a pair of upright metal pillars, an outside panel connecting said pillars at the outer side of the door, a sheet metal inside panel connecting said pillars at the inner side of the door, a trim panel overlying said inside metal panel, and a sheet metal reinforcing member secured to said pillars and inside panel and forming therewith, and independently of said outside panel and trim panel, a boxed stiffening section adjacent the bottom of the door. 95
7. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 100
8. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 105
9. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 110
10. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 115
11. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 120
12. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 125
13. A sheet metal door for closed automobile bodies including a pair of upright pillars, a header connecting said pillars at the top, an outside panel connecting said pillars at the outer side of the door and having a window opening, an inside panel connecting said pillars at the inner side of the door below said window opening, and a reinforcing member secured to said pillars and inside panel and forming therewith and independently of said outside panel a boxed stiffening section adjacent the bottom of the door. 130

8. A door for automobile bodies, including a pair of upright metal pillars, a sheet metal panel connecting said pillars, and a sheet metal member secured to said panel, at least 5 one of said last named parts being of angular cross-section to form with the other a hollow box girder member connecting said pillars adjacent the bottom of the door.
9. A sheet metal door for closed automobile bodies including a pair of upright pillars, a header connecting said pillars at the top, an outside panel connecting said pillars at the outer side of the door and having a window opening, an inside panel connecting 10 said pillars at the inner side of the door below said window opening, and having a bottom flange to engage the threshold, the lower edge of said outside panel being crimped over said flange, and a member secured to 15 said inside panel, at least one of said last named parts being of angular cross-section to form with the other a hollow box girder member connecting said pillars adjacent the bottom of the door.
10. A sheet metal door for automobile bodies including a pair of upright pillars, an outside panel connecting said pillars at the outer side of the door, an inside panel connecting said pillars at the inner side of the 20 door, said inside panel having at its lower end a portion turned outwardly, thence downwardly, and thence again outwardly and connected with said outside panel, and a box member of angular cross-section having 25 a relatively long vertical leg secured at its lower end to said downwardly turned portion of said inside panel and a relatively short horizontal leg secured to said inside panel above the lower end portion thereof, the ends 30 of said legs being secured to said pillars.
11. A sheet metal door for closed automobile bodies including a pair of upright pillars having webs disposed transversely of the door, and a header connecting said pillars at the top, said header comprising a 35 channel member disposed with its web vertical, said header web having end portions secured to the webs of said pillars.
12. A sheet metal door for closed automobile bodies including a pair of upright pillars having webs disposed transversely of the door and inner flanges with outwardly turned edges, a header connecting said pillars at the top, said header comprising a 40 channel member disposed with its web vertical, said header web having end portions secured to the web of said pillars, and window guides of channel cross section secured 45 at their upper ends to the web of said header and having flanges secured to the turned edges of said pillar flanges.
13. A sheet metal door for closed automobile bodies including a pair of upright pillars, a hollow sheet metal box girder member 50 forming a rigid connection between said pillars adjacent the bottom, and a window bumper carried by the top of said member.
14. In a door for closed automobile bodies, a pair of upright pillars, window guides carried by said pillars, a window glass in said 70 guides, a door header permanently connecting said pillars at the top and located outwardly of the plane of said guides and glass to permit the latter to be inserted into and removed from said guides at the top, and a trim header detachably secured to said door header and normally closing the upper ends of said guides.
15. In a door for closed automobile bodies, a pair of upright pillars, window guides carried by said pillars, a window glass in said 75 guides, a door header permanently connecting said pillars at the top and located outwardly of the plane of said guides and glass to permit the latter to be inserted into and removed from said guides at the top, and a trim header detachably secured to said door header and normally closing the upper ends of said guides, said trim header carrying a 80 packing header to engage the upper edge of 85 said glass.
16. In a door for automobile bodies, a pair of metal pillars having inner flanges formed at their edges with integral offset lips and an inside trim panel having its lateral edges 90 inserted under said lips and secured in place 95 thereby.
17. In a door for closed automobile bodies, a pair of upright metal pillars, a metal panel connecting said pillars, window guides carried by said pillars, a window glass in said 100 guides, a trim panel, a belt trim molding secured to said metal panel and having its lower edge overlying the upper edge of said trim panel to secure the latter in place at the top, and a weather strip carried by said molding and engaging said glass.
18. In a door for closed automobile bodies, a pair of upright metal pillars, a metal panel connecting said pillars, a trim panel, a bottom molding secured to said metal panel and overlying the lower edge of said trim panel to secure the latter in place at the bottom, and a seal carried by said molding to engage 105 the threshold.
19. In a door for closed automobile bodies, a pair of metal pillars having inner flanges formed at their edges with lips, a metal panel connecting said flanges, a trim panel having its lateral edges engaged and secured in place 110 by said lips, a belt trim molding secured to said metal panel and having its lower edge overlying the upper edge of said trim panel to secure the latter in place at the top, and a bottom molding secured to said metal panel and overlying the lower edge of said trim panel to secure said trim panel in place at 115 the bottom.
- In testimony whereof I affix my signature.
MILLARD H. TONCRAY.
